UNITED STATES PATENT OFFICE

ANTONY JACK CAGLIOSTRO, OF NEW YORK, N. Y.

COPYHOLDER

Application filed September 29, 1930. Serial No. 485,228.

This invention relates to copy holders and has for an object to provide a copy holder which may be installed as a permanent fixture on the typewriter support of a drop top typewriter desk and will be collapsible so as to permit of the drop top being closed in the usual manner to house both the typewriter and the copy holder.

A further object of the invention is to provide a copy holder which may be disposed as a permanent fixture on the typewriter support of the drop top desk directly in rear of the typewriter and will embody both an extensible standard and an extensible stem 13 for the operating key whereby the copy may be held on a level with the operator's eyes when in use and after use the operator need only loosen two set screws in order to collapse the standard and operating key stem 20 to retract or condense the device in a small compact form so that the drop top of the desk may be closed thereover when the device is not in use.

A still further object of the invention is to provide a copy holder which will be formed of a few simple, strong and durable parts which will withstand severe conditions of service without easily getting out of order.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a perspective view of my improved copy holder;

Fig. 2 is a side elevation of the copy holder;

Fig. 3 is a fragmentary rear elevation of the copy holder with parts in section;

Fig. 4 is a detail view showing one of the tension springs for tensioning the feed rollers, taken on line 4-4 of Fig. 3;

Fig. 5 is a detail sectional view showing

the backing, line gauge, and feed rollers, taken on line 5-5 of Fig. 3,

Fig. 6 is a detail plan view showing the rock lever and its support, taken on line 6-6 of Fig. 4,

Fig. 7 is a detail perspective view of the rock lever support, and

Fig. 8 is a fragmentary side elevation similar to Fig. 4 but showing the slot for limiting movement of the tensioning device.

Referring now to the drawings in which like characters of reference designate similar parts, 10 designates a conventional typewriter, 11 the typewriter support of a drop top typewriter desk, and 12 the drop top in raised position. These parts are of the usual and well known construction and form no part of the invention.

In carrying out the invention, I provide a standard 13 comprising a tubular base member 14 and an extensible rod member 15 telescoping into the base member. The base member is provided at the bottom with a transverse foot or base 16 which may be permanently secured to the typewriter support 11 by screws 17 or otherwise in rear of the typewriter.

By referring now to Fig. 3, it will be seen that the extension member is provided with a longitudinal groove 18 which receives a tongue 19 carried in a housing 20 formed integral with and extending laterally from the top of the base member 14. A helical spring 21 is disposed in the housing and is confined under tension between a screw plug 22 threaded into the end of the housing and the tongue 19. The spring urges the tongue outwardly to frictionally engage in the groove 18 and performs the dual function of preventing relative rotation of the base member and extension member and frictionally retarding extension and retraction of said members.

A set screw 23 is screwed into the upper end of the base member 14 and bears against the extension member 15 and forms means for rigidly securing the extension member in extended or retracted position.

Preferably the base member 14 is somewhat less in height than the height of the typewriter so that when the extension member is re-

tracted thereinto, the drop top 12 of the typewriter desk may be closed in the usual manner. Since the device is rigidly secured to the typewriter support, it moves as a unit 5 with the support and typewriter when the drop top is being closed.

Disposed transversely across the top of the extension member 14 is a bar 24 which is preferably formed of an aluminum casting and is 10 provided at the ends with inverted T-shaped extensions 25, as best shown in Figures 3 and 8, the purpose of which will presently be explained. The bar is provided centrally on the back thereof with an integral lug 26, best 15 shown in Figs. 3 and 5. The lug is provided with a vertical opening 27 to receive the extension member 15 and a set screw 28 is threaded into the side of the lug and bears against the extension member to detachably 20 secure the bar to said member.

The bar 24 forms a backing for the copy 29. A line gauge 30 is secured at the ends by screws 31 or otherwise to the front face of the bar and functions in the usual manner to 25 designate the lines of the copy when the hereinafter mentioned feed rollers are actuated to feed the copy longitudinally between the bar 24 and the line gauge.

As shown in Figure 6, a pair of feed rollers 30 32 and 33 are provided with reduced ends which are journaled in suitable openings formed in the above mentioned inverted T-shaped extension 25. The roller 33 is equipped with a ratchet 34. The roller 32 is 35 spring pressed against the roller 33 and rotates as a unit therewith and oppositely thereto when the ratchet 34 is rotated. A spring pressed pin 35, best shown in Figs. 6 and 8, is slidably fitted in a suitable opening 40 in each of the inverted T-shaped extensions 25 and bears against the reduced end of the roller 32. A spring 36 is disposed in rear of each pin and is held under tension against the pin by a screw 37. The screw may be advanced 45 or retracted to vary the tension of the spring. Obviously, the openings, in which the reduced ends of the friction roller 32 are journaled, are elongated to form slots 38, best 50 shown in Fig. 8, to permit of the roller being spring pressed against the roller 33 by the pins 35, as just described.

For actuating the ratchet 34 a pawl 38 is provided, as best shown in Figs. 1 and 2. The pawl is pivoted at one end to one leg 55 of a V-shaped lever 39, the latter being pivoted at the apex, as shown at 40, to a lug 41 which is formed integral with a casting 42, best shown in Fig. 7. The casting is provided with a rectangular opening 43 to receive the end of one of the T-shaped extensions 25, as best shown in Fig. 6, and a set screw 44 is threaded into the side of the casting and engages said extension to adjustably 60 secure the casting thereto. When the lever 65 is rocked on its pivot, the pawl advances the

ratchet step by step in the usual manner, and to assure positive operation of the pawl, the free end thereof is preferably weighted, as shown at 45 in Figure 1. The pawl may be rocked outwardly on its pivot to disengage the pawl from the ratchet when it is desired to feed the rollers manually, and for the latter purpose a knurled head 46 is formed integral with the feed roller 33 at the opposite end thereof from the ratchet.

As best shown in Figs. 1 and 2, a key 47 is preferably pivoted centrally on a lug 48 which is formed integral with a base plate 49. The base plate is preferably provided with securing screws 50 which rigidly secure the key to the typewriter support 11 laterally of the standard 13 where it may be conveniently struck by the operator to operate the ratchet and pawl feeding device.

The key is operatively connected to the above described V-shaped lever 39 by means of an extensible stem 51. The stem comprises preferably a rod base member 52 and a tubular extension member 53 into which the base member telescopes when the standard is retracted or depressed to collapse the copy holder. The extensible stem is adjusted vertically by means of a set screw 54 to correspond in height to the height of the standard. The stem is pivotally connected, as shown at 55, to the key and is pivotally connected, as shown at 56 to the V-shaped lever. When the key is depressed by the operator, the extensible stem will be moved vertically to rock the V-shaped lever and cause the pawl to advance the ratchet one step whereby the copy is advanced one line past the line gauge, as will be easily understood.

For limiting the play of the key 47, a screw 57 is threaded into the base plate 49 on one side of the pivot lug or standard 48 of the key, and a second screw 58 is threaded into the base on the opposite side of said standard. The screw 57 limits downward movement of the key to lift the extensible stem while the screw 58 limits return movement of the key due to the action of a spring pressed pin 59 which is mounted on the base between the screw 57 and standard 48 and bears against the underneath edge of the lever. By advancing or retracting the screws 57 and 58 as desired, the play of the key may be regulated.

From the above description it will be seen that by simply loosening the set screws 23 of the standard and 54 of the extensible stem, the copy holder may be retracted or lowered to correspond in height to substantially the height of the typewriter so that the device 120 will permit of the drop top 12 of the typewriter desk being closed. It will be further observed that the copy holder is associated with the typewriter support as a permanent 125 installation in contradistinction to the usual 130

copy holder which must be removed from operative position to permit closing of the drop top of the desk.

Having thus described the invention, I claim:

1. A copy holder for drop top typewriter desks comprising a vertically adjustable standard adapted to be retracted to substantially the height of the typewriter whereby to fit underneath the closed drop top of the typewriter desk and adapted to be extended to support copy above and in the rear of the typewriter, a vertically adjustable key stem disposed laterally of the standard and adapted to be retracted and extended to correspond in height to the standard and cooperate therewith, a copy holding bar associated with the top of the standard centrally thereof and provided with a lug adapted to receive a portion of the vertically adjustable standard, means carried by the lug for locking the bar in position on the standard, inverted T-shaped extensions carried on the ends of the bar and integral therewith, said extensions comprising vertical legs and forwardly and rearwardly extending legs, a roller having its end portions journaled in corresponding forwardly extending legs, a second roller having its end portions journaled in said corresponding rearwardly extending legs and adapted to cooperate with said first-mentioned roller, a ratchet and pawl feeding device operated by said key stem for actuating one of said rollers, and a pivoted key adapted to be permanently secured to a typewriter support of the desk and operatively connected to the key stem for actuating said stem.

2. A copy holder for drop top typewriter desks comprising a vertically collapsible standard, a vertically collapsible key stem disposed laterally of the standard, a key for actuating said stem, means for securing the standard and key rigidly to the typewriter support, said standard and said stem being collapsible to fit underneath the closed drop top of the desk, a transverse bar carried by said standard and provided with an inverted T-shaped extension at each end, said extensions being provided with forwardly and rearwardly extending legs, a roller having its ends journaled in corresponding forwardly extending legs of said extension, a second roller carried by corresponding rearwardly extending legs and adapted to cooperate with said first-mentioned roller, a ratchet carried by the last-mentioned roller, a casting adjustable on one of said rearwardly extending legs and having a lug, a V-shaped lever having its apex pivoted on said lug, a pivoted pawl carried by one leg of said lever and engaging said ratchet, said adjustable casting being adapted to permit ready adjustment or removal of the pawl from the bar, and a pivotal connection between the other leg of said lever and said stem.

3. A device of the class described including a vertically collapsible standard comprising a base member adapted to be permanently secured to a typewriter support of a desk and an extension member telescoping into the base member, said extension member having a longitudinal groove, a spring-pressed tongue adapted to engage in the groove and prevent rotation of said extension member, a transverse bar associated with the extension member and provided with an integral lug centrally thereof, said lug being adapted to receive the upper end portion of said extension member, means carried by the lug for locking said bar to said extension member, a T-shaped extension carried by the bar at each end thereof and integral therewith, said T-shaped extension including forwardly and rearwardly extending legs, a roller having its end portions journaled in corresponding forwardly extending legs, a second roller having its end portions journaled in corresponding rearwardly extending legs and being adapted to cooperate with said first-mentioned roller, said second roller having a ratchet, a casting adjustable on one of said rearwardly extending legs and being provided with a lug, a lever having its apex pivoted to said lug and being formed with legs, a pawl pivotally connected to one of said legs and being adapted to engage said ratchet, and means connected to the other of said legs whereby said lever may be shifted for rotating the ratchet and causing copy to be fed step by step between the rollers.

In testimony whereof I affix my signature.
ANTONY JACK CAGLIOSTRO. [L. S.]
